CLAIM

The ornamental design for a bouillon cup or similar
article, as shown and described.

DESCRIPTION

FIG. 1 is a side elevational view of a bouillon cup or
similar article showing my new design, the opposite side
view being a mirror image thereof;

FIG. 2 is a bottom plan view thereof;

FIG. 3 is a sectional view taken along line 3—3 of FIG.
2;

FIG. 4 is a front elevational view thereof with the ele-
vational view of the opposite side being a mirror image
thereof; and

FIG. 5 is a top plan view thereof.
